(57) **CLAIM**

I claim the ornamental design for a vehicle sensor, as shown and described.

DESCRIPTION

FIG. 1 is a perspective view from the top and left side of a vehicle sensor in accordance with said design;

FIG. 2 is a perspective view from the bottom and right side of the vehicle sensor of FIG. 1;

FIG. 3 is a left side elevation view of the vehicle sensor of FIG. 1;

FIG. 4 is a front elevation view of the vehicle sensor of FIG. 1;

FIG. 5 is a right side elevation view of the vehicle sensor of FIG. 1;

FIG. 6 is a rear elevation view of the vehicle sensor of FIG. 1;

FIG. 7 is a top plan view of the vehicle sensor of FIG. 1;

FIG. 8 is a bottom plan view of the vehicle sensor of FIG. 1; and,

FIG. 9 is a perspective view showing the use of the vehicle sensor of FIG. 1, in which the vehicle sensor is plugged into the OBD-II port of a vehicle.

The dash-dash broken lines shown in FIGS. 1 through 9 show portions of the vehicle sensor that form no part of the claimed design.

The dash-dot-dash broken lines shown in FIG. 9 are for the purpose of showing environmental structure and form no part of the claimed design.
